UNITED STATES PATENT OFFICE.

CADY B. DURHAM, OF FLINT, MICHIGAN, ASSIGNOR TO GENERAL MOTORS CORPORATION, OF DETROIT, MICHIGAN, A CORPORATION OF DELAWARE.

CYLINDER FOR INTERNAL-COMBUSTION ENGINES.

Application filed October 9, 1922. Serial No. 593,306.

To all whom it may concern:

Be it known that I, CADY B. DURHAM, a citizen of the United States of America, and a resident of Flint, county of Genesee, and State of Michigan, have invented certain new and useful Improvements in Cylinders for Internal-Combustion Engines, of which the following is a full, clear, concise, and exact description, such as will enable others skilled in the art to which the invention relates to make and use the same, reference being made therein to the accompanying drawings, which form a part of this specification.

My invention relates to the manufacture of cylinders for internal combustion engines from cast metal, and is characterized by the chilling of the inner surface thereof with which the piston moves in contact in the completed engine. Such cylinders are commonly made from cast iron which metal, in its ordinary form, is apt to be lacking in hardness and density, and provides an unsatisfactory surface for the piston to move over. I have found, however, that a much better wearing surface and one less likely to be injured when the cylinder is in use is secured if the inner surface thereof is chilled during the casting operations; the increased hardness and density produced by chilling providing a surface which, when finished to size as by grinding or otherwise, provides a surface which may be better and more efficiently lubricated, as well also as a surface with which the piston is less likely to seize should the supply of lubricant thereto be unduly reduced or interrupted; and a wearing surface which in general is more perfect than has heretofore been the case. Pistons made from aluminum or an alloy including aluminum as its principal ingredient, such as are in extensive use at the present time, are found work much better with such a chilled surface or cylinder wall than with an unchilled cast iron surface; and a cylinder made in accordance with my invention has enhanced wearing qualities because of the increased hardness and density of cylinder wall resulting from the chilling of the material thereof during the casting operation.

My invention is regarded as including certain improvements in and relating to the art, method or process of producing internal combustion engine cylinders from cast

metal, as well also as in a core used in the casting thereof and in the cylinder produced in accordance with such method and by the use of said core; and is so claimed in the claims at the end of this specification 60 wherein the distinguishing features of my invention are particularly pointed out.

In the drawing accompanying and forming a part of this specification:

Figure 1 is a plan view showing a mold 65 used in producing an internal combustion engine cylinder block made up of two cylinders in accordance with my invention, the upper portion of the mold being omitted.

Figure 2 is a view showing the lower mold section shown in Figure 1 in section upon a vertical plane extending along the axis of one of the cylinders, the core being shown in side elevation.

Figure 3 is a view showing a section upon 75 a transverse vertical plane indicated by the line 3, 3, Figure 1.

Figure 4 is a view showing a transverse section of one of the two parts of a core box used in making the core contemplated 80 in my invention.

Referring now to the drawing, the reference numeral 5 designates a lower mold section comprising a flask member or frame 6 filled with sand and the upper surface of 85 which has (by the use of a suitable pattern and during suitable filling and ramming operations) been given a contour corresponding with that of one half the external configuration of the cylinder block to 90 be produced, as is usual in molding operations. The upper flask section and corresponding mold part is not shown as my invention is not concerned with the mold sections whereby the proper external form is 95 imparted to the cylinder block produced in accordance with my invention.

Supported within the mold cavity corresponding with the external contour of the cylinder block produced is a suitable core 100 comprising cylindrical portions 7, 7 which provide the bores of the two cylinders of the block, and other portions 8 (not involved in my invention) whereby the inlet, the exhaust and spark plug passages of the block 105 are provided. The core is supported from its ends by lugs 9, 9 fitting within recesses provided in the external mold sections by core prints upon the cylinder block pattern, or otherwise, in accordance with schemes 110

well known in the molding art. The numeral 10 designates a jacket core designed to provide the cooling water jacket space of the cylinder block, the same being supported from the external mold sections by lugs 11 in substantially the same way as the main core which provides the internal bores of the cylinders.

10 The cylindrical bore forming portions 7, 7 of the core are provided with chilling devices or chilling means which may be of various specific forms, but which are shown as made up of a plurality of plates 12 of cast iron, steel or equivalent material, 15 curved in cross section so as to correspond with the curvature of the inner surfaces of the cylinders to be produced; said plates being spaced slightly apart from one another and disposed circumferentially of the cores 20 so as to provide substantially continuous chill members or devices with which the molten metal contacts as it is poured into the mold. These chilling members are shown as of a length corresponding approximately with that of the portions of the cylinders over which the pistons move in the completed engine, as those parts of the interior of the cylinders with which the pistons contact should be of uniform hardness, texture and composition throughout; although the inner surfaces of the combustion chambers and the lower ends of the cylinders not uncovered by the pistons, such portions being beyond the limits of travel 30 of the pistons, are preferably left unchilled: such end being attained by making the chilling members shorter than the interior bores of the cylinders, as will be appreciated.

40 In forming the core the backs or inner faces of the metallic plates 12 are preferably coated with a suitable paste or cement to secure a more perfect joint between them and the sand from which the core is formed, and then placed in a suitable core box indicated by the numeral 13 in Figure 4; the plates being spaced properly apart by lugs 45 14 in the bottom of the core box. The core box is then filled with core sand and dried

and baked, the complete core being made up of two similar parts cemented together as is usual in core making practice. The side edges of the chills 12 are preferably beveled as shown, and the longitudinal grooves between adjacent edges of the plates as well as the holes left by the lugs 14 upon removing the core sections from the core box will be filled in with core sand in order to provide a smooth exterior core surface, as will be understood.

Obviously the chill plates may be anchored to the body of the core by simply embedding them or portions of them therein, instead of by using a cement or adhesive for that purpose, and, while I have disclosed my invention as employed in the production of a cylinder block having two cylinders the same is equally applicable for the production of cylinder blocks having more than two individual cylinders, or for the production of single cylinders for use in internal combustion engines.

Having thus described and explained my invention, I claim and desire to secure by Letters Patent:

1. A sand core for use in forming an internal combustion engine cylinder from cast metal, said core having chilling means adapted to chill the internal surface of a cylinder produced by the use of said core.

2. A sand core for use in producing an internal combustion engine cylinder from cast metal, said core comprising a cylindrical portion having one or more curved metallic plates adapted to chill the interior of a cylinder formed by the use of said core.

3. A sand core for use in making an internal combustion engine cylinder from cast metal, said core comprising a cylindrical portion, and a plurality of segmental metallic plates extending along and spaced circumferentially about and embedded in said cylindrical core and adapted to chill the internal surface of a cylinder produced by the use of said core.

In testimony whereof I affix my signature.

CADY B. DURHAM.
